UNITED STATES PATENT OFFICE

121,795

DESIGN FOR A TEXTILE FABRIC OR SIMILAR ARTICLE

Aaron Rosenstein, New York, N. Y.

Application June 20, 1940, Serial No. 93,159

Term of patent 3½ years

To all whom it may concern:

Be it known that Aaron Rosenstein, a citizen of the United States, residing in the city, county, and State of New York, has invented a new, original, and ornamental design for a Textile Fabric or Similar Article, of which the following is a specification, reference being had to the accompanying drawing, forming a part thereof.

The figure of the drawing is a plan view of a textile fabric or similar article showing my new design.

The design consists of a tinsel woven floral-like pattern arranged on a plain background, as shown.

I claim:

The ornamental design for a textile fabric or similar article, as shown and described.

AARON ROSENSTEIN.
